AUTOMATIC RELEASE AERIAL DELIVERY
CONTAINERFrank G. Manson and James J. Maskey,
Dayton, Ohio

Application February 18, 1943, Serial No. 476,286

6 Claims. (Cl. 244—137)

(Granted under the act of March 3, 1883, as
amended April 30, 1928; 370 O. G. 757)

The invention described herein may be manufactured and used by or for the Government for governmental purposes, without the payment to use of any royalty thereon.

This invention relates to containers for safely delivering articles of a breakable nature by dropping them from aircraft by parachute, and is particularly applicable where the time in which the container may be opened and the contents removed must be kept at a minimum, as for instance where rifles, machine guns, etc., are dropped to paratroops at or near a scene of action.

Many containers of this class have recently been developed, but so far as is known, all are delivered closed with some sort of a fastener which must be opened before the contents may be removed.

It is therefore an object of this invention to provide a container of this general class but which has automatic means, operative by impact of the container on the ground, for undoing the fasteners which hold the device closed.

One of the difficulties encountered in developing a container with automatic opening mechanism responsive to impact has been that the tendency of a parachute, upon landing its load, is to drag the load along on the ground a considerable distance, and when this happens after the container has been automatically opened by impact, the contents are strewn and scattered over a wide area, which not only retards their recovery by the paratroops but may considerably damage such precision instruments as present-day weapons, by dragging them over muddy or stony terrain.

It is therefore another object of this invention to provide means, which may also be responsive to the same impact mechanism as opens the container, to completely disconnect the parachute from the container at the instant of landing.

A further difficulty encountered in the development of this invention has been that, when an impact mechanism has been provided which will satisfactorily open the container and disconnect the parachute upon landing, the same impact mechanism is also readily operable accidentally, so that too great care to prevent accidental operation of the automatic opening and releasing mechanism is required between the time that the container is packed and the time it is taken aloft and intentionally dropped.

It is therefore another object of this invention to provide a locking device which will hold the automatic impact-responsive opening and releas-

ing mechanism in a locked state, such locking device being undone automatically at the time the container leaves the aircraft on its way to the ground.

5 Other objects and advantages will be recognized as the invention is further described and reference is made to the drawings, wherein:

Fig. 1 is an elevational view of the improved container, part being shown in section to disclose 10 the operating mechanism.

Fig. 2 is a fragmentary view similar to Fig. 1 but with the impact mechanism unlocked and operable as when the container has dropped far enough to effect its release.

15 Fig. 3 is a transverse section taken at 3—3 of Fig. 1, showing the fasteners undone and the one half of the container swung to partly open position.

Fig. 4 shows one of the fasteners in the closed 20 position.

Like numerals refer to like parts throughout the several views of the drawings.

The embodiment of the invention herein shown 25 may, for illustrative purposes, be divided into three main parts—the parachute housing 10, the load carrying compartment 12, and the impact-responsive mechanism 14 which operates the automatic opening and parachute-disconnecting means.

30 The parachute housing 10 comprises a sheet metal cylinder 16 turned over at the top as at 18 and provided with a circular bottom 20 having a rim 22. About half of the rim 22 extends into the cylinder 16, to which it may be spot-welded or similarly secured. The other half of the rim 22 protrudes from the cylinder 16 and extends into the load compartment 12. A cup-shaped cover 24 may preferably be made of waterproof fabric, with an elastic band 26 around the open end of the cover.

35 The band 26 serves to hold the open end of the cover snugged up to the cylinder 16, making a waterproof joint, and also provides the necessary friction to yieldingly hold the cover 40 in place, yet allow it to be pulled off with a moderate pull at the closed end. The bottom 20 carries pairs of lugs 17 between which the risers 19 of a parachute 21 are releasably held by pull pins 23. A static line 25 has its end stitched by a

45 light break cord to the top of the parachute as at 27, the cover 24 having a central opening 29 through which the top of the parachute is exposed for connection to the static line.

50 The impact-responsive mechanism 14 is contained in a frusto-conical shell 28, flanged in-

wardly at 30 and provided with a circular base member 32 having a rim 34 which may be spot-welded to the shell or be similarly secured.

The load-carrying compartment 12 comprises two semicylindrical parts 36 and 38 (see Fig. 3), both of which lap over and rest on the rim 22 at one end, and the shell 28 at the other end. Axially spaced reinforcing bands are also made up of semicircular straps 40 and 42, these straps being secured, preferably by spot-welding, to the semicylindrical parts 36 and 38 respectively.

Straps 40 and 42, where they come together at one of the junctions between the semicylindrical parts, are formed into hinge joints 44, and where they abut at the other juncture between the cylinder halves, are provided with a hasp-and-staple connection consisting of a hasp 46 hinged at 48 and secured to the strap 42 by rivets 50, and a staple 52 welded or similarly secured at the end of the strap 40.

Where the upper semicylindrical part 36 laps over and rests on the rim 22 and shell 28, it is preferably spot-welded or otherwise secured to these parts. The lower semicylindrical part 38, however, is left free to swing open on the hinge 44 when the hasp-and-staple connection is undone (see Fig. 3).

Within the shell 28 a flanged hub 54 is secured to the base member 32 by any suitable means. A guide tube 56 is fastened in the hub and a pilot tube 58 is slidable in said guide tube. On the outer end of the pilot tube 58 is secured a flanged hub 60 which is in turn fastened to the bumper member 62.

Struts 64 and 66 support a washer 68 upon which one end of a spring 70 rests, the other end reacting against the bumper 62 to urge it outwardly. An outwardly turned flange 72 engages the inturned flange 30 to limit outward movement of the bumper 62. A collar 74 pinned to the pilot tube 58 is provided for engaging the outer end of the guide tube 56 to limit inward movement of the bumper.

Clamped to the outside of the guide tube 56 is a split collar 76, one side having a pair of ears 78 through which a bolt 80 may pass to clamp the collar in position on the tube. Opposite the ears 78 a bracket 82 extends from the collar outwardly and carries, at its outer end, a small grooved pulley 84. A cable 86 has a washer 88 fastened to its inner end, the washer resting on the inner end of the pilot tube 58, and the cable passing outwardly through a slot 90 in the tube, over the pulley 84, and through several lengths of conduit 92, 94, and 96 into the parachute housing 10. The lengths of conduit are supported on the upper semicylindrical part 36 by brackets 98 which are secured to this cylindrical part by rivets or similar fastening means.

Intermediate interfacing ends of the conduits 92 and 94, and intermediate interfacing ends of the conduits 94 and 96, the cable 86 has spliced thereto the short lengths of cable which carry the pull pins 100 (see Fig. 4), which pass through the staples 52 and over the hasps 46 to hold the load-carrying compartment 12 closed.

After the cable 86 passes through the conduit 96 into the parachute housing 10 it is divided into two branches, a branch extending to each pull pin 23, the two of which hold the parachute risers 19 fast to the lugs 17 until the pins are withdrawn. A handle 102 attached to a short length of cable 104 which is spliced into the main cable 86 and brought out through an opening in the conduit 92, is provided for opening the load cham-

ber and disconnecting the parachute risers manually when that becomes desirable.

The safety device which prevents pulling of the pins 100 and 23, by inadvertent or accidental impact on the bumper 62, consists of a pawl 106 which is pivotally supported between the ears 78 on the bolt 80. The nose of this pawl is turned downward and extends through a loose hole in the guide tube 56 into a somewhat closer fitting hole in the pilot tube 58. As long as the nose of this pawl extends into the hole in the pilot tube 58, the bumper cannot be operated.

To hold the nose of the pawl 106 in the locked position shown in Fig. 1, a cable 108 is fastened to the heel end of the pawl and passes through the conduit 110 into the parachute housing 10. The conduit 110 is held positioned on the semicylindrical post 36 by a bracket 112.

The extreme upper end of the cable 108 is formed into an eye 109 through which a break cord 114 extends in joining the cable to the static line 25. In order that the eye 109 may come adjacent the lower end of the static line 25 for connection thereto without requiring too great accuracy in the length of the cable 108, an extension coil spring 116 is interposed in the cable within the shell 28, whereby the cable may be stretched as required, thereby putting the spring in tension and holding the pawl 106 with its nose extending downward through the hole in the pilot tube 58. A washer 117 limits the amount of extension of the spring 116. The bumper 62 is in this manner held locked against movement as long as the break cord 114 is not ruptured.

When the break cord 114 tears and the tension in the spring 116 is released, a light expansion spring 118 (see Fig. 2) raises the nose of the pawl out of the hole in the pilot tube 58 and thereby conditions the apparatus for operation by the impact bumper 62. Links 120 are provided for launching the apparatus from a bomb rack.

The operation of the device is as follows:

With the semicylindrical part 38 swung to open position on its hinge 44, the load-carrying compartment 12 is packed with rifles or similar devices with such packing interspersed as the nature of the goods requires. The part 38 is then swung to closed position, the hasps 46 put over the staples 52, and the pins 100 inserted in the staples over the hasps (see Fig. 4).

The loops of the parachute risers 19 are now laid between the lugs 17, then the pins 23 are inserted through the loops. The parachute is next packed in the housing 10 in the usual manner and the cover 24 applied. The eye 109 of the cable 108 is drawn to the opening 29 of the cover and joined to the static line 25 by the break cord 114. This tilts the nose of the pawl 106 downward into the hole in the pilot tube 58 and locks the bumper 62 against movement. The top of the canopy of the parachute is also joined to the static line by the break cord 27. The device is now in condition to be handled without danger of operating the impact releasing mechanism accidentally.

The device may be launched from an aircraft in any manner desired, but may preferably be carried on the bomb rack by the links 120, the free end of the static line 25 being attached by a suitable means to the aircraft. When released, the device drops until the static line 25 is tautened. This pulls on the cable 108, extending the spring 116 until the washer 117 encounters the end of the conduit 110, whereupon the break cord 114 tears, slacking the cable 108 and spring 116, al-

lowing the lighter spring 118 to move the pawl 186 to the unlocked position shown in Fig. 2.

As soon as the break cord 114 is torn, the static line 25 starts to withdraw the parachute 21 from the housing 10 after first removing the cover 24. When the canopy is withdrawn full length, the break cord 27 tears, the canopy opens, and the device moves at reduced speed to the ground.

When striking the ground, the impact on the bumper 62 telescopes the tubes 56 and 58, and, by drawing the cable 86 over the pulley 84, withdraws the pins 100 to open the load compartment 12, and simultaneously withdraws the pins 23 to disconnect the parachute from the container so that the open container will not be dragged and the contents will not, therefore, be scattered. Obviously, a minimum of time is required for the paratroops to remove the contents, since no latches, buckles, or similar fasteners are provided which need be opened manually after the container has alighted.

Having described our invention, we claim:

1. An automatic release aerial delivery container comprising, in combination, a hollow receptacle, transverse partitions dividing said receptacle into three compartments, a parachute in one end compartment, operating mechanism in the other end compartment, an access door in the intermediate compartment for entry and removal of the articles to be delivered, attaching means in the parachute compartment for holding the parachute risers, means for releasing said attaching means, locking means on said access door for releasably holding said door closed, said operating mechanism comprising an impact responsive member with means for connecting said impact responsive member to said locking means and said releasing means, operative upon impact to release said risers and said locking means, latch means normally engaged for securing said impact member against movement by impact, means interconnecting said latch means and said parachute, operative to release said latch means by partial withdrawal of said parachute from the parachute compartment, and manual means for operating said connecting means.

2. An automatic release aerial delivery container, comprising, in combination, a hollow receptacle, transverse partitions dividing said receptacle into three compartments, a parachute in one end compartment, operating mechanism in the other end compartment, an access door in the intermediate compartment for entry and removal of the articles to be delivered, attaching means in the parachute compartment for holding the parachute risers, means for releasing said attaching means, locking means on said access door for releasably holding said door closed, the operating mechanism comprising an impact-responsive member with means connecting said impact-responsive member to said locking means and said releasing means, operative upon impact to release said risers and said locking means, latch means normally engaged for securing said impact member against movement by impact, means interconnecting said latch means and said parachute, operative to release said latch means by withdrawal of said parachute from the parachute compartment.

3. An automatic release aerial delivery container, comprising, in combination, a hollow receptacle, partitions dividing said receptacle into three compartments, a parachute in one compartment, operating mechanism in another compartment, an access door in the third compartment for entry and removal of the articles to be delivered, releasable means in the parachute compartment for attaching the parachute risers, locking means on said access door for holding said door closed, the operating mechanism comprising an impact-responsive member with means connecting said impact-responsive member to said releasable means, operative upon impact to release said risers, latch means normally engaged for securing said impact member against movement by impact, means interconnecting said latch means and said parachute, operative to release said latch means by withdrawal of said parachute from the parachute compartment.

4. An automatic release aerial delivery container, comprising, in combination, a hollow receptacle, a parachute in one part of said receptacle, operating mechanism in another part of said receptacle, an access door in said receptacle for entry and removal of the articles to be delivered, means secured to the receptacle for holding the parachute risers, locking means on said access door for releasably holding said door closed, the operating mechanism comprising an impact-responsive member with means connecting said impact-responsive member to said locking means, operative upon impact to release said locking means, latch means normally engaged for securing said impact member against movement by impact, means interconnecting said latch means and said parachute, operative to release said latch means by partial withdrawal of said parachute from the receptacle.

5. An automatic release aerial delivery container, comprising, in combination, a hollow receptacle, a parachute in one part of said receptacle, operating mechanism in another part of said receptacle, an access door in said receptacle for entry and removal of the articles to be delivered, releasable means on said receptacle for attaching the parachute risers, locking means on said access door for releasably holding said door closed, the operating mechanism comprising an impact-responsive member with means connecting said impact-responsive member to said locking means and said releasable means, operative upon impact to release said risers and said locking means.

6. An automatic release aerial delivery container, comprising, in combination, a hollow receptacle, a parachute in one part of said receptacle, operating mechanism in another part of said receptacle, an access door in said receptacle for entry and removal of the articles to be delivered, locking means on said access door for releasably holding said door closed, the operating mechanism comprising an impact-responsive member with means connecting said impact-responsive member to said locking means, operative upon impact to release said locking means.
